PROCESS OF REFINING GLYCERIDE OIL IN
A LIQUID PARAFFINIC SOLVENT WITH A
CONCENTRATED ALCOHOLIC ALKALI
METAL HYDROXIDE SOLUTIONArnold L. Ayers, Bartlesville, Okla., assignor to
Phillips Petroleum Company, a corporation of
Delaware

Application January 4, 1949, Serial No. 69,104

14 Claims. (Cl. 260—426)

1

This invention relates to a method of treating glyceride oils. In a more specific aspect, it relates to a method of treating glyceride oils to remove undesirable constituents. In another specific aspect, it relates to a method for removing free fatty acids, color bodies, non-drying constituents, and "break" formers from a glyceride oil. In still another specific aspect, it relates to a single-treatment method of refining glyceride oils. More specifically, it relates to a method of refining soy bean oil.

The glyceride oils with which this invention is concerned, are animal and vegetable oils, the latter of which are obtained from seeds, usually by pressing or by extraction with a suitable solvent. Some of the commonly used glyceride oils are linseed oil, tung oil, soy bean oil, cotton seed oil, corn oil, and peanut oil. While these oils have wide use in the preparation of foods, my invention is likewise concerned with the preparation of these oils as film-forming constituents, such as in paints, varnishes, enamels, synthetic resins, soap, plastics, drug products, and the like.

Ordinarily, glyceride oils, both those obtained by pressing and by extraction with solvents contain about 0.5 to 1 per cent of phosphatides and 1 to 2 per cent of free fatty acids. In addition, there is a certain content of color bodies, non-drying constituents, and materials which cause "break" or sludge formation upon heating. In preparing oils for such industrial uses, it is necessary that these undesirable constituents be removed.

Conventional methods of refining vegetable oils involve the use of large volumes of concentrated reagents such as sulfuric acid or sodium hydroxide, which often tend to char or coagulate the by-products of the oil. In addition, these reagents have a harmful effect on the drying or film-forming characteristics of the oil. In my copending application, Serial No. 17,105, filed March 25, 1948, for "A Process for Refining Soy Bean Oil," I have disclosed a method of refining soy bean oil comprising the steps of extracting the oil with an alcohol-water solution followed by treatment with a dilute caustic solution.

I have now discovered a method of refining vegetable oils which involves a single treatment with an alcoholic solution of an alkali metal hydroxide.

It is therefore an object of my invention to provide a method for refining glyceride oils wherein a minimum amount of equipment is required.

It is another object of my invention to provide

2

a method for removing undesirable constituents from a glyceride oil.

It is still another object of my invention to provide a single-treatment method for refining glyceride oils.

It is another object of my invention to provide a method for refining soy bean oil with a minimum loss of oil.

Other objects and advantages of my invention will be apparent to those skilled in the art upon reading the following drawing, disclosure and claims.

The single drawing is a flow sheet showing the steps involved in a continuous process for the refining of glyceride oils according to my invention.

In the drawing, raw oil feed line 2 and hydrocarbon solvent feed line 3 lead to mixer 4, from which outlet line 6 leads to extractor 1 for transferring the solvent-oil miscella from said mixer to said extractor. Entering the top of extractor 1 is a feed line 8 for introducing alcoholic caustic solution and leaving the bottom of said extractor is an outlet line 9 for removing the spent caustic. Leaving the top of said extractor is an outlet line 10 for transferring the miscella to a separator 11 for complete removal of the spent caustic through line 12. From said separator, a miscella outlet line 13 leads to flash distillation chamber 14 from which the vaporized hydrocarbon leaves an upper portion through line 16 and the refined oil leaves at the bottom through line 17. Hydrocarbon vapor line 16 enters condenser 18 from which the condensed hydrocarbon is removed through line 19 into hydrocarbon feed line 3.

Operation

I have found that glyceride oils can be refined by a single treatment with an alcoholic solution of an alkali metal hydroxide. To my knowledge, it has never been tried or even realized that the extraction and neutralization steps could be combined into a single treatment, but I have found that glyceride oils can be efficiently refined by such a single treatment.

In carrying out my invention, I prefer to form a solvent-oil miscella by dissolving one part of the crude oil in from one to six parts of a liquid hydrocarbon solvent, preferably n-hexane, neo-hexane, n-heptane, isohexane, isoheptane, or n-pentane. This miscella is treated by intimately contacting it with an alcoholic alkali metal hydroxide solution. The contacting is carried out by any of the usual methods of establishing liquid-liquid contact between two immiscible liquids. While I prefer to use methyl

alcohol, ethyl or isopropyl alcohol may be used instead. It is not necessary that absolute alcohol be used but the alcoholic content should be between 75 and 100 per cent, the higher water contents being desirable when operating at higher temperatures, as hereafter disclosed. I may use from 0.02 to 5 grams of alkali metal hydroxide per 100 grams of oil treated, the exact amount depending on the free fatty acid content of the oil.

The amount of caustic should be approximately that amount necessary to completely neutralize the free fatty acids of the oil. Sodium hydroxide is preferable because it is effective and is cheap, but potassium and lithium hydroxides may be used. In carrying out the liquid-liquid extraction, I prefer that the contact time be between 5 and 30 minutes and that the temperature be between 0 and 30° C., although temperatures between -20 to 130° C. may be employed. The pressure is adjusted to maintain the reactants in the liquid phase.

The volume ratio of alcohol to glyceride oil should be from 0.2:1 to 50:1, the preferred range being from 2:1 to 20:1.

After contact between the miscella and alcoholic caustic has been maintained for a sufficiently long time, the mixture is allowed to settle and the oily miscella is separated from the spent caustic solution. The oil and spent caustic solutions can be separated by gravity when operating under preferred conditions of high solvent to oil ratio because the miscella will be of sufficiently low density to allow the spent caustic to settle. However, when the specific gravity of the miscella and the caustic solution are more nearly equal, the separation may be made by means of a centrifuge or its equivalent.

The paraffinic solvent added to the oil in forming the original miscella is removed by distillation, preferably, at atmospheric pressure, the temperature to which it must be heated, of course, being dependent on the boiling point of the solvent used. It is not desirable to heat the oil to a much higher temperature than is necessary to distill the solvent.

After such a treatment as I have just described, the refined oil will be of good color and will ordinarily contain less than 0.1 per cent of free fatty acid. The content of the break or sludge formers will be correspondingly lowered.

My invention may be carried out as a batch process or the process may be continuous, as shown in the drawing. The drawing represents the apparatus adapted to carrying out a process wherein the density of miscella is sufficiently below that of the caustic solution to permit countercurrent flow of liquids through the extractor. The separator, which may be a centrifuge or any equivalent, permits more complete separation of miscella and spent caustic.

By carrying out the neutralization and alcohol extraction in a single step, the process is considerably simplified. The amount of equipment is reduced because one extractor and separator are used to carry out a treatment formerly requiring two reactors and two separators. This means a shorter treating cycle for refining the oil than is required in the two-stage process. Reducing the amount of equipment also reduces the capital investment, which means an increased amount of material may be processed per unit cost. Another advantage of reduced amount of equipment is a reduced amount of oil lost during processing because of leaks in equip-

ment and oil dissolved in treating liquids. Eliminating one step of the process reduces the operating and maintenance costs.

In my process the concentration of caustic in the alcohol-caustic treating fluid is lower than the concentration normally employed in the neutralizing fluid of a two-step process. This means less corrosion of equipment and less hydrolysis of the oil during treatment. Numerous other advantages will be apparent to those skilled in the art.

The use of mixtures of the suitable solvents and/or mixtures of the caustic materials is fully within the intended scope of my invention. My invention may be employed in the refining of innumerable oils which can be refined by caustic treatment and alcohol extraction.

The advantages of my invention will be more clearly understood from the following examples:

Example I

A miscella of 25.6 grams of soybean oil in 100 grams of neohexane was treated with 100 grams of 99% methyl alcohol containing 0.04 gram of sodium hydroxide. The mixture was shaken well and allowed to separate. The two phases were separated by decanting. The oil was recovered from the hydrocarbon phase by vaporizing off the hydrocarbon at atmospheric pressure and a temperature of 60° C. A total of 25.4 grams of refined oil containing only 0.085% free fatty acid was obtained.

Example II

A miscella containing 26.3 grams of oil in 106 grams of neohexane was heated and mixed with 100 grams of 99% methyl alcohol containing 10 ml. of a 0.1052 N-potassium hydroxide solution. The mixture was allowed to settle and the hydrocarbon phase was separated by decanting. The hydrocarbon was removed from the oil by distillation at atmospheric pressure and a temperature of 60° C. Twenty-six and four-tenths grams of refined oil was recovered. This oil was light colored and contained only 0.058% free fatty acid. (The slight excess yield of refined oil is probably due to incomplete removal of solvent.)

The specific examples are presented to illustrate and explain the advantages of my process and are not to be considered as limiting my invention, the scope of which is defined by the following claims.

I claim:

1. The process of refining a glyceride oil which comprises intimately contacting a solvent-oil miscella comprising a solution of said oil in from 1 to 6 volumes of a liquid hydrocarbon for a period of time from 5 to 30 minutes at a temperature of from -20 to 130° C. with an alcoholic alkali metal hydroxide solution consisting essentially of from 75 to 100 per cent alcohol, 0.02 to 5 grams of alkali metal hydroxide per 100 grams of oil and water whenever the concentration of the alcohol employed is less than 100 per cent the ratio of alcohol to oil being from .2 to 50 volumes of said alcohol per volume of oil, separating the miscella from the caustic solution and separating the resulting miscella into the solvent and oil fractions.

2. The process for refining a glyceride oil which comprises intimately contacting a solvent-oil miscella comprising a solution of said oil in from 1 to 6 volumes of a liquid paraffinic hydrocarbon for from 5 to 10 minutes at a temperature from 0 to 30° C. with an alcoholic alkali

metal hydroxide solution consisting essentially of 75 to 100 per cent alcohol, 0.02 to 5 grams of alkali metal hydroxide per 100 grams of oil, and water whenever the concentration of the alcohol employed is less than 100 per cent, the ratio of alcohol to oil being from .2 to 50 volumes of alcohol per volume of oil, separating the miscella from the caustic solution and separating the resulting miscella into the solvent and oil fractions.

3. The process for refining a glyceride oil which comprises intimately contacting a solvent-oil miscella comprising a solution of said oil in from 1 to 6 volumes of a liquid paraffinic hydrocarbon for from 5 to 10 minutes at a temperature from 0 to 30° C. with an alcoholic caustic solution containing essentially from 75 to 100 per cent alcohol, 0.02 to 5 grams of alkali metal hydroxide per 100 grams of oil, the ratio of alcohol to oil and water whenever the concentration of the alcohol employed is less than 100 per cent, being from 2 to 20 volumes of alcohol per volume of oil, separating the miscella from the caustic solution and separating the resulting miscella into the solvent and oil fractions.

4. The process for refining a glyceride oil which comprises intimately contacting a solvent-oil miscella comprising a solution of said oil in from 1 to 6 volumes of a liquid paraffinic hydrocarbon for from 5 to 10 minutes at a temperature from 0 to 30° C. with an alcoholic caustic solution containing essentially from 75 to 100 per cent methyl alcohol, from 0.02 to 5 grams of alkali metal hydroxide per 100 grams of oil and water whenever the concentration of the alcohol employed is less than 100 per cent, the ratio of alcohol to oil being from 2 to 20 volumes of said alcohol per volume of oil, separating the miscella from the caustic solution and separating the resulting miscella into the solvent and oil fractions.

5. The process of refining a glyceride oil which comprises intimately contacting a miscella of said oil in a liquid paraffinic solvent with a concentrated alcoholic alkali metal hydroxide solution consisting essentially of 75-100 percent alcohol, alkali metal hydroxide, and water whenever the concentration of the alcohol employed is less than 100 percent, for a period of time sufficient to neutralize the free fatty acids and to extract the

alcohol-soluble bodies, separating the spent alcoholic caustic solution from the miscella and separating the paraffinic solvent from the refined oil.

- 5 6. The process of claim 5 wherein the alcohol is methyl alcohol.
- 7. The process of claim 5 wherein the alcohol is ethyl alcohol.
- 8. The process of claim 5 wherein the alcohol is isopropyl alcohol.
- 10 9. The process of claim 5 wherein the paraffinic solvent is neohexane.
- 15 10. The process of claim 5 wherein the paraffinic solvent is n-hexane.
- 11. The process of claim 5 wherein the paraffinic solvent is n-pentane.
- 12. The process of claim 5 wherein the alkali metal hydroxide is sodium hydroxide.
- 20 13. The process of claim 5 wherein the alkali metal hydroxide is potassium hydroxide.
- 25 14. The process of refining a crude soy bean oil which comprises intimately contacting a miscella of one volume of said oil in from 4 to 6 volumes of neohexane at a temperature between 0 and 30° C. for a period of time from 5 to 10 minutes with a 90 to 100 per cent methyl alcohol solution containing from 0.02 to 5 grams of alkali metal hydroxide per 100 grams of oil, separating said miscella from the spent alcoholic caustic solution and heating the separated miscella to distill the paraffinic solvent.
